UNITED STATES PATENT OFFICE.

THOMAS LAFFEY, OF PITTSBURG, PENNSYLVANIA, ASSIGNOR OF ONE-HALF
TO ALBERT C. WETTENGEL, OF SAME PLACE.

WASHING-MACHINE.

SPECIFICATION forming part of Letters Patent No. 429,538, dated June 3, 1890.

Application filed August 3, 1889. Serial No. 319,696. (No model.)

To all whom it may concern:

Be it known that I, THOMAS LAFFEY, a citizen of the United States, residing at Pittsburg, in the county of Allegheny and State of Pennsylvania, have invented certain new and useful Improvements in Washing-Machines; and I do hereby declare the following to be a full, clear, and exact description of the invention, such as will enable others skilled in the art to which it pertains to make and use the same, reference being had to the accompanying drawings, which form a part of this specification.

My invention relates to an improvement in washing-machines; and it consists in a circular tub having a revolving false bottom with two vertically-operating rollers revolving on the top of the same, together with certain details of construction and combination of parts, as will be fully described hereinafter.

In the accompanying drawings, Figure 1 is a plan view of my improved washing-machine with the top thereof partly broken away. Fig. 2 is a sectional elevation of the same. Fig. 3 is an enlarged transverse sectional view through the vertical driving-shaft, the cylindrical fixed casing, and the spiral pressure-spring on the line $x-x$. Fig. 4 is a perspective view of one of the vertical guides. Fig. 5 is a vertical sectional view through one-half of the machine on the line $y-y$ of Fig. 1.

To put my invention into practice, I provide a tub a , of suitable size and form of construction, and place in the bottom of the same on a pivot b a false bottom c , having radially attached thereto a series of wooden or other rubbers d , and the said bottom c capable of being given a rapid rotary movement by means of a vertical shaft e , attached thereto, and geared to a crank-shaft f by small bevel-pinnions g . Surrounding this vertical shaft e is a casing i , which is provided with longitudinal slots at diametrically-opposite points, and is fixed at its upper end to the cover of the tub, said fixed slotted casing having an inclosed spiral spring o . On opposite sides of the tub a are attached vertical guides k , in which one end of the two shafts l operate. These horizontal shafts l are fitted at their inner approximate ends in the longitudinal slots of the vertical fixed casing and at their

outer ends in the longitudinal slots of the vertical fixed guides, said shafts being free to play vertically in the guides and casing and being guided by said parts. The inner ends 55 of the shafts are arranged in the slotted casing so that the lower end of the coiled spring o bears thereon, and each shaft carries a roller m , which bears upon the fabrics as they are carried around in the tub by the rotary 60 false bottom c of the machine.

In operation the clothes to be washed are thrown on the top of the bottom c and sufficient water let into the tub a . The crank p is now revolved, which operation revolves the 65 shaft e , the bevel-gearing g , and vertical shaft i and bottom c . This bottom, being in rapid motion, carries the clothes beneath the rollers m and rotates the rollers by friction. The friction generated by the rotary movement of the bottom c and that of the two rollers m rapidly washes the clothes.

Having thus described my invention, what I claim, and desire to secure by Letters Patent, is—

75

1. In a washing-machine such as described, the combination consisting of the tub a , having a revolving false bottom c , operating on a pivot b , the vertical shaft e , attached thereto, the bevel-gearing g and crank-shaft f , the 80 two rollers m , capable of a limited vertical movement and operated by the friction of the revolving bottom c , the casing i and spring o , and the guides k , attached to opposite sides of the tub a for bearings for the 85 roller-shafts l , substantially as described.

2. In a washing-machine, the combination, with a receptacle and a rotary bottom, of a vertical tube or casing arranged centrally within the receptacle, the vertical fixed guides 90 arranged on the sides of the tub, the independent horizontal shafts fitted in said fixed guides and in guides on the central tube and carrying the rollers, which are adapted to be driven by frictional contact with the rotary bottom, and a pressure-spring for depressing the horizontal shafts and rollers, substantially as described.

3. In a washing-machine, substantially as described, the combination, with a tub or receptacle and a vertical shaft carrying a rotary bottom, of a vertical fixed casing or tube

arranged around the shaft and having the longitudinal slots, the vertical slotted guides fixed to the tub, the horizontal shafts carrying the rollers and having their ends fitted in the slots of the vertical tube and guides, and a pressure-spring housed within the vertical tube or casing and bearing on the approximate ends of both horizontal shafts, substantially as described.

In testimony that I claim the foregoing I do hereunto affix my signature this 19th day of March, A. D. 1889.

THOMAS LAFFEY. [L. S.]

In presence of—
C. C. LEE,
M. E. HARRISON.
